US00D644624S

(12) **United States Design Patent**
Akana et al.

(10) **Patent No.:** **US D644,624 S**
(45) **Date of Patent:** **** Sep. 6, 2011**

(54) **ELECTRONIC DEVICE**

(75) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Daniele De Iuliis**, San Francisco, CA (US); **Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Portola Valley, CA (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/386,812**

(22) Filed: **Mar. 4, 2011**

CLAIM

The ornamental design for an electronic device, as shown and described.

DESCRIPTION

FIG. 1 is a bottom front perspective view of an electronic device showing our new design;

FIG. 2 is a bottom rear perspective view thereof;

FIG. 3 is front view thereof;

FIG. 4 is rear view thereof;

FIG. 5 is a top plan view thereof;

FIG. 6 is a left side view thereof;

FIG. 7 is a right side view thereof;

FIG. 8 is bottom plan view thereof;

FIG. 9 is a top rear perspective view thereof; and,

FIG. 10 is a top front perspective view thereof.

The broken lines in the Figures show portions of the electronic device which form no part of the claimed design.
